UNITED STATES PATENT OFFICE.

CLINTON L. ROSSITER, JR., OF BROOKLYN, NEW YORK, ASSIGNOR TO UNDERWOOD TYPEWRITER COMPANY, OF NEW YORK, N. Y., A CORPORATION OF DELAWARE.

TYPEWRITING-MACHINE SUPPORT.

Application filed March 8, 1922. Serial No. 541,922.

To all whom it may concern:

Be it known that I, CLINTON L. ROSSITER, Jr., a citizen of the United States, residing in Brooklyn Borough, in the county of 5 Kings, city and State of New York, have invented certain new and useful Improvements in Typewriting-Machine Supports, of which the following is a specification.

The present invention relates to means for 10 holding a typewriting machine, more particularly a machine of the so-called portable class, for operation thereof on the lap of the operator.

In some instances, as in the Army, where 15 often no table can be procured, the use of a portable typewriter is difficult.

To overcome this difficulty, there is devised a lap-board to which the portable typewriter is secured, and at the same time 20 there are overcome difficulties due to the jerky movements of the typewriter carriage. This carriage is started and stopped at each type-impression, and jars the keys, which are independently movable and which are 25 easily jarred, tiring and injuring the eyes of the user. This difficulty is overcome by anchoring the machine to the legs of the user, so that he can hold the machine rigidly. The anchorage overcomes the tendency 30 of the typewriter to jerk or creep to the left due to the sidewise step-by-step movements of the carriage. It also overcomes the tendency of the typewriter and lap-board to jerk or creep to the right. As a 35 part of the anchorage for this purpose, there is employed a strap upon which the typewriter and lap-board hang, the strap encircling the trunk of the user and being adjustable to secure the positioning of the key- 40 board relatively to the hands of the user. The weight of the typewriter and lap-board tend to cause it to slide away from the body, this tendency being resisted due to the hanging of the typewriter and lap-board 45 upon the strap. Thus the typewriter is anchored against jerking movement to the left and to the right, and also against movement away from the trunk, while the weight of the typewriter and board prevents 50 movement towards the trunk of the user. While the leg clasps act to prevent sidewise creeping or jerking in both directions by reason of the carriage movements, still a typewriting machine is a very live

subject, and constantly tends to creep wherever it can, and that, owing to its inclined position, it will creep and slide downwardly away from the user, notwithstanding the leg clasps, and hence the anchorage for the machine includes the trunk straps which prevent such creeping. 55

The anchorages comprise detachable devices which are self-locking in slotted plates provided upon the edge portions of the lap-board, so that when the anchorages are removed from the locking slots, the cover of the portable typewriter may be set down upon the machine and fit closely over the edges of the lap-board, to which it is secured in the usual manner, the cover having 65 the usual handle so that the whole device is similar to a satchel. 70

Other features of the invention are the provision of holding devices, of the character mentioned, adjustable laterally to the 75 position and lines of the thighs of the operator; and of holding devices adjustable to permit the machine to be held at such distance from the operator's trunk as may be most suitable for writing. 80

A further feature of the invention is the provision of readily attachable and detachable connections for the holding devices, so that the machine may be expeditiously and in a simple manner placed or removed by 85 the operator; and in this connection the invention, in the preferred embodiment thereof, comprises means whereby the weight of the machine, due to the natural tendency of the machine to slide forward, serves to maintain the correct operating position, and to maintain the holding connections in locked condition. 90

A further feature of the invention is the provision of holding devices capable of being placed with the machine in the usual casing, and of means for securing the holding devices in place in the casing, with the machine, when the machine is not in use. 95

Figure 1 is a view, in side elevation, showing the typewriting machine held in place on the lap of the operator. 100

Figure 2 is a view looking toward the operator at the machine, and showing the lateral retaining devices. 105

Figure 3 is a view, in cross-sectional side elevation, through the casing, the machine being diagrammatically shown therein and

the lateral retaining devices being shown in the position in which they are carried when not in use.

Figure 4 is a view in cross-section on the line 4-4 of Figure 3.

Figure 5 is a top plan view of a piece of the baseboard, and of the connections of the holding devices thereto; the board being shown partly in cross-section for clear illustration of certain details of the connections.

Figure 6 is a view in cross-section on the line 6-6 of Figure 5.

Figure 7 is a view, in side elevation, of the assembly shown in Figure 5.

15 In Figures 1 and 2 a portable typewriting machine 10, having the usual letter-feeding carriage 10^a is shown as secured to the operator 11 by a strap 12, passing around the 20 waist of the operator to prevent the machine from sliding forward, and by sheet-metal arms 13 which, by engagement with the sides of the operator's legs, prevent lateral displacement of the machine. These holding devices and the means by which they are 25 connected to the machine or its support are as follows:

The machine shown is mounted upon and fixed to a baseboard 14. As shown in Figure 6, the baseboard 14 has a peripheral flange 15 in which the machine is held. Set 30 in countersinks in the bottom and sides of the baseboard, and secured thereto by screws 16, one at each side of the baseboard, are angle-pieces or brackets 17, one wing 18 of 35 each of which brackets is set in the bottom of the baseboard, and the other wing 19 of each of which brackets is set in the side of the baseboard. The outside faces of the brackets are preferably flush with the faces of the 40 baseboard into which they are set. The brackets are in opposite sides of the baseboard, and are about centrally thereof, as indicated in Figure 1.

In the horizontal under wing 18 of each 45 bracket is a slot 20 extending in a direction transverse to the baseboard. Above the bracket-wing 18 and over the slot 20 is a recess 21 in the baseboard. The recess 21, as shown in Figure 5, is wider than the slot 20 50 to accommodate the head 22 of the arm or retaining device 13 on that side of the baseboard. The head 22 (see Figures 6 and 7) is shown at the end of a neck-portion 24 of the retaining device, formed by lateral cuts

55. The retaining devices 13 are curved to partially embrace the outside of the thighs of the operator, and the portions comprising the necks 24 and heads 22 are offset, as shown in Figure 6, to project vertically into 60 the baseboard when in use. The slots 20 are of such length that, when the retaining devices are turned ninety degrees from their Figure 6 position, the heads 22 thereof may be passed through the slots 20 and into the 65 recesses 21; and are wide enough to accom-

modate the necks 24 of the retaining devices to permit the latter to be turned to their Figure 6 holding position. The width of the recesses 21 is such as to permit the heads 22 of the retaining devices to be turned with 70 the latter to Figure 6 position.

In the side walls of the baseboard opposite the bracket-wings 19 are elongated horizontal recesses 26. In each bracket-wing 19, opposite the corresponding recess 26, is an elongated horizontal slot 27, the rear end of which is enlarged at 28 to permit passage therethrough of a retaining head or button 29 on the end of a strap 30. The width of the slot 27 forward of the opening 28 is such as to accommodate and permit sliding movement therewith of the neck or pin 31 of the button 29, but is too narrow to permit the button to be disengaged from the bracket, except by movement of the button 35 into registration with the enlarged opening 28. The recess 26 behind the slot 27 is of a width to accommodate and permit movement therewith of the button 29. The strap 30 on the left-hand side of the baseboard (see Figure 1) is a short strap carrying a buckle 32. The strap connecting with the right-hand side of the baseboard is the strap 12 which embraces the operator's waist. The strap 12 is adjustably connected to the strap 30, and, for this purpose, the strap 12 has eyes or holes 33 therewith, near one end thereof, after the fashion of the usual belt, for adjustable connection to the buckle 32 on the strap 30. This adjustment permits the machine to be set on the operator's knees in whatever position is most convenient. Ordinarily, the slightly inclined natural position of the legs will cause the machine to slide outward from the operator as far as 105 the strap 12 permits; and the position so assumed by the machine, due to its weight, will remain fixed by reason of the strap.

For holding the machine against lateral slip, the operator's knees are spread, as indicated in Figure 2, to bear firmly against the side retaining devices 13. Preferably, the arms 13 have spring action to accommodate themselves to the shape and position of the operator's legs; and, to the same 110 end, the devices 13 may have a limited pivotal movement where the necks thereof engage the slots 20 in the brackets.

To remove the arms 13, it is simply necessary to turn the same at right angles to the Figure 6 position, and slide the same along the slots 20 until the heads 22 thereof may be withdrawn through the slots. To disconnect the straps 12 and 30, the machine is drawn toward the operator until the buttons 29 register with the openings 28 in the side wings of the brackets, whereupon the buttons are drawn outward through the openings 28.

For holding the retaining devices 13 in 120

the casing with the machine when the latter is not in use, a clip 34, preferably of spring sheet-metal, is riveted or otherwise secured at 35 to the under side of the top of the casing-cover 36, having the usual handle 36a. On either side of the attachment 35 the arms of the clip 34 are slightly offset at 37 to permit the ends of the retaining devices 13 to be slipped between the same and 10 the top of the cover, so as to be held to the latter by the spring action of the arms of the clip.

Variations may be resorted to within the scope of the invention, and portions of the 15 improvements may be used without others.

Having thus described my invention, I claim:

1. A new article of manufacture comprising a lap board for holding a typewriting machine stationarily on the lap of the typist, said board having means around its periphery engaging the sides of the typewriting machine base to center the typewriting machine thereon, and prevent its 25 sliding on the surface of the board while being used, said board also having devices thereon for attachment of anchors, anchors comprising clasps attachable to the devices and extending below the bottom of said 30 board and adapted to rest on the sides of the legs of the typist and a belt for anchoring the board to the trunk of the typist and attachable to said devices on the board.

35 2. A new article of manufacture comprising a lap board for holding a typewriting machine stationarily on the lap of the typist, said board having around its periphery a flange for engaging the sides of 40 the base of the typewriting machine to center the machine thereon and prevent sliding on the surface of the board while being used, anchorage means for steadyng the board and typewriter and preventing 45 creeping movement of the board in either sidewise direction and enabling the weight of the typewriting machine to steady the keyboard and locate it relatively to the hands of the user, said anchorage means 50 comprising clasps detachably mounted upon the bottom of the lap board and anchoring it to the legs of the user, and also comprising an adjustable belt detachably connected to the side edges of the lap board 55 and anchoring it to the trunk of the user.

3. A new article of manufacture comprising a lap board for holding a typewriting machine stationarily on the lap of the typist, said board having means around 60 its periphery for engaging the sides of the typewriter base and having anchorage means for steadyng it and preventing creeping movements of the board in either sidewise direction and enabling the weight 65 of the machine to steady the key board and

locate it relatively to the hands of the user, said anchorage means comprising clasps detachably mounted upon the bottom of the lap board and anchoring it to the legs of the user and also comprising an adjustable belt detachably connected to the side edges of the lap board and anchoring it to the trunk of the user, said lap board having two surface plates, one secured to each of its side edge portions, said plates provided 70 with two sets of slots, said clasp being removably self-locking in one set of said slots and said belt having ends which are removably self-locking in the other set of said slots. 80

4. A new article of manufacture comprising a lap board for holding a typewriter machine stationarily on the lap of the typist, anchorage means steadyng the board and preventing creeping movements of the 85 board in either sidewise direction, said anchorage means comprising clasps detachably mounted upon the bottom of the lap board and anchoring it to the legs of the user and also comprising a belt detachably 90 connected to the side edges of the lap board and anchoring it to the trunk of the user, said lap board having two surface plates, one secured to each of its side edge portions, said plates provided with 95 two sets of slots, said clasp being removably self-locking in one set of said slots and said belt having ends which are removably self locking in the other set of said slots, said plates being angle plates comprising wings covering recesses formed in the bottom and the side edges of said board, the side wings having the slots for said belt ends and the bottom wings having the slots for said clasps. 100

5. A new article of manufacture comprising a lap board for holding a typewriting machine stationarily on the lap of the typist, said board having means around its periphery for engaging the sides of the base of the typewriting machine to center the typewriting machine thereon, anchorage means for steadyng the board and prevent creeping movement of the board in either sidewise direction, said anchorage means 110 comprising clasps for anchoring the lap board to the legs of the user, said lap board having surface plates secured to its side edge portions, the plates being provided with slots and the clasps being removably self-locking in said slots, a belt for passing around the trunk of the typist and attachable at either end to said plates, and a cover fitting around the edges of the lap board and removably attached thereto to 115 form a satchel. 120
